UNITED STATES PATENT OFFICE.

FRANK P. NOURSE, OF LEWISTON, IDAHO.

EXTENSION-SPLINT.

1,164,956.

Specification of Letters Patent.

Patented Dec. 21, 1915.

Application filed July 29, 1914, Serial No. 853,900. Renewed August 27, 1915. Serial No. 47,686.

To all whom it may concern:

Be it known that I, FRANK P. NOURSE, a citizen of the United States, residing at Lewiston, in the county of Nez Perce and State of Idaho, have invented new and useful Improvements in Extension-Splints, of which the following is a specification.

My invention relates to extension splints for surgical use, especially in treating fractures and disease of the legs, and one of its objects is to provide a splint which may be easily applied, worn with ease and comfort by the patient, and adjusted as occasion may require to extend the limb or to adjust the foot of the patient as may be found necessary or advisable in treatment or to give relief to the patient.

A further object of the invention is to provide a splint which may be firmly anchored to the body and limb and employed for periodical extension, so as to overcome well known objections to continuous extension splints, and by means of which the reference being had to the accompanying drawings is carried out with mathematical accuracy.

A still further object of the invention is to provide a splint which may be firmly anchored by means of adhesive plaster and bandages, and which affords other advantages and conveniences.

The invention consists of the features of construction, combination and arrangement of parts herein fully described and claimed, reference being had to the accompanying drawings in which:—

Figure 1 is a side view showing the application of the invention. Fig. 2 is a top plan view of the same, parts appearing in section. Figs. 3 and 4 are views illustrating the manner of applying the upper holding strips. Fig. 5 is a view of the foot plate and lower holding strips. Fig. 6 is an outer end elevation of the foot receptacle and coacting parts. Fig. 7 is a vertical longitudinal section thereof. Fig. 8 is a sectional view through the bearing plate and clamp.

The device comprises an upper bearing and clamping member 1, and a lower foot engaging and supporting member 2, coupled by adjustable connections, as herein-after described. The member 1 consists of a plate 3 of metal or other suitable material having a leather facing 4, and provided at its outer or upper end with a hooked

clamping member 5, adapted for coöperation with a relatively adjustable clamping member 6, said plate 3 being provided with a receiving loop 7, for a purpose hereinafter set forth.

The leg engaging and supporting member 2 comprises a box like foot receptacle 8, which is open at top, bottom, and at its inner side. Disposed within said receptacle and between the side walls thereof is a foot plate 9, of proper size to rest against the bottom of the foot of the leg to be treated. This foot plate is provided with a projecting screw stem 10 which passes through a vertical slot 11 in the outer wall of the receptacle and receives a clamping nut 12. Said outer wall of the receptacle has a depending portion 13 provided with a notch or slot 14, opening through its lower edge, which depending portion of the wall is arranged to bear against the outer face of a cross bar 15, against which the lower edge of the foot plate 9 normally rests. This cross bar 15 is provided with a screw stem 16 projecting through the notch 14 and provided with a nut 17, whereby the receptacle is adapted to be detachably applied to the cross bar. The stem 10 and nut 12 also adapt the foot plate 9 to be adjusted vertically in the slot 11, for the purpose of disposing said foot plate at a desired elevation with relation to the cross bar.

A connecting means is provided between the members 1 and 2, whereby said members are coupled together to hold the injured leg extended, and by means of which the leg may be extended within desired limits. This connecting means comprises threaded rods 18 and 19, the former having an offset end 20 to engage the loops 7 and a reduced terminal 21 to interlock with a notch 22 in the clamping member 6, and the latter having an offset end 23 terminating in a reduced threaded extension 24 passing through the bar 15 and provided with a clamping nut 25. Engaging said threaded rods 18 and 19 are adjusting nuts 26 and 27 connected or arranged to bear respectively against the relative or outer ends of short and long tubes 28 and 29 fitted upon said rods, between which tubes are disposed one or more intermediate filler tubes 30 as required according to the length of the connection, one end of each tube having a joint sleeve 31 to telescopically receive the join-

ing end of the adjacent tube, whereby the tubes are connected by slip-joint couplings, allowing them to be connected and disconnected at will. It will, of course, be understood that the intermediate or filler tubes 30 may be of varying lengths, so that proper tubes may be fitted together to form an extension connection between the elements 1 and 2 of proper length according to the length of the affected part and the degree of extension to be employed.

In applying the improved splint for use as an extension splint for a fractured leg, suitable anchoring means for the element 1 and part 9 of the element 2 are employed. The anchoring means associated with the part 1 at the upper end of the body comprises a series of strips 32, 33 and 34 of surgeons' plaster. The strip 32 extends longitudinally along the outer side of the body from the axilla to the hip, while the strips 33 and 34 extend in opposite directions respectively from the axilla over the front of the body to the adjacent hip, and from the axilla across the back of the body to the opposite hip. The adjacent ends of these strips are then joined and lapped to form the tongue 35. The element 1 is then arranged to bear against the crossed portions of the strips or at the axilla, and the tongue 35 bent backwardly into engagement with the hook 5 and held pressed therein by the clamping member 6, with which the reduced end 21 of the threaded rod 18 is then engaged to hold the parts in clamping position. A broad binder or bandage 36 is then firmly applied over the strips and element 1 and about the body from the element 1 to the hips and firmly secured with safety pins. A strip 37 of surgeons' plaster is then extended centrally across the foot plate 9 and terminally along each side of the leg to which it firmly adheres. After which the foot plate is fitted within the receptacle 2 and secured in position so that it will rest upon the cross bar 15 which supports the foot from the bed or couch, after which the nuts 26 and 27 are properly adjusted and the tubes 28, 29 and 30 applied to form the stretcher or extension connection and brace to hold the limb rigidly in set position, the leg being bandaged from the ankle to the knee, as indicated at 38. A placing of the splint is then completed, and the extension of the limb should then be commenced and carried out as follows:—With the hands grasping the bar 15, the leg is slightly raised from the bed by gently pulling, the leg is then drawn out until a part 60 of the shortening is overcome, but in this operation not much force is employed, as the plasters, as yet, have not become thoroughly or fully seated. The nuts are then set so that the splint will hold the extension beam, and this process of extension is peri-

odically repeated, the leg being drawn out a little each day for four or five days until the extension is fully completed. By this method of periodical extension, which the present device allows of in a ready, convenient and effective manner the well known objections to continuous extensions is avoided and the patient granted long intervals of rest and relaxation between the extension period. This mode of periodical and fractionally extending the limb reduces the amount of worry and anxiety on the part of the patient and avoids the natural tendency of the patient to work his body toward the foot of the bed until the foot reaches a point of resistance to gain relief, allowing the ends of the fractured bone to again overlap, the objections to which are evident. The present device overcomes these and other objections, and hence allows the patient to have a greater degree of comfort and to sleep well. The desired advantages are gained by the use of anchorages of adhesive plaster, which render the present form of extension splint possible and practicable, the device as a whole being applied directly to the body.

It will be apparent from the foregoing that by means of my improved splint the leg can be extended with almost mathematical accuracy, while the patient is permitted to move about in bed and may be bolstered up with pillows, so that he can read or take food and drink readily. It will be observed that the threaded extension rods are bent or offset so that the extension tube is disposed a sufficient distance from the leg to allow of the application of a plaster of Paris cast, or retention splints, or dressings as the case may require. Should it be desired to rotate the foot, either outward or inward, this may be done by loosening the lower nut 16, turning the foot and receptacle in the desired direction and then retightening the nut. It often happens that the resting of the heel of the foot on the bed irritates the heel to a painful degree. This may be overcome by loosening the nut 12, raising the foot plate 9, by which the foot will be elevated, and then retightening the nut. By this means the heel may be raised to any point desired for the purpose of relief. Where separation of joint is required, as in case of disease, or for operation on the joint, the leg may be extended to the desired degree by the extension means within the discretion of the surgeon.

I claim:—

1. In an extension splint, the combination of a body engaging member, a foot plate, a box-like receptacle in which said foot plate is disposed, an adjustable connection between said foot plate and receptacle, a bar carrying said receptacle, rods carried by the body engaging member and the said bar, 125

and a sectional connection between said rods, the sections of said connection being detachably coupled.

2. In an extension splint, the combination 5 of a body engaging member, a foot plate, a box like receptacle in which said foot plate is disposed and with which said foot plate is connected, a bar carrying said box like receptacle, and threaded rods carried by the 10 body engaging member and the said bar, nuts adjustably engaging said threaded rods, and a sectional connection between the rods and terminally engaged by the nuts, the sections of said connection being detachably coupled.

3. In an extension splint element, the combination of a body engaging member, a box like receptacle, a foot plate adapted to

bear against the sole of the foot of the wearer, said plate being disposed within and 20 adjustably mounted upon said box like receptacle, a cross bar, means for detachably and adjustably connecting said box like receptacle with said cross bar, threaded rods carried by the body engaging member and 25 cross bar, nuts upon said rods, and an extensible connection engaging the ends of the threaded rods and disposed between the nuts.

In testimony whereof I affix my signature 30 in presence of two witnesses.

FRANK P. NOURSE.
